United States Patent Office

Des. 188,489
Patented Aug. 2, 1960

188,489

DAVENPORT

Carl L. Otto, New York, N.Y., assignor to Heywood-Wakefield Company, Gardner, Mass., a corporation of Massachusetts

Filed Aug. 10, 1959, Ser. No. 57,119

Term of patent 7 years

(Cl. D15—11)

FIG. 1.

FIG. 2.

FIG. 3.

Fig. 1 is a front perspective view of a davenport embodying my new design;

Fig. 2 is a side elevation thereof; and

Fig. 3 is a top plan view on a somewhat smaller scale. The back of the article is conventional.

I claim:

The ornamental design for a davenport, substantially as shown and described.
